UNITED STATES PATENT OFFICE.

ALBERT STORER, OF BOSTON, MASSACHUSETTS, ASSIGNOR TO GEORGE W. GREGORY, OF SAME PLACE.

POLARIZED BELL.

SPECIFICATION forming part of Letters Patent No. 451,414, dated April 28, 1891.

Application filed August 7, 1890. Serial No. 361,285. (No model.)

To all whom it may concern. -

Be it known that I, ALBERT STORER, of Boston, county of Suffolk, State of Massachusetts, have invented an Improvement in Po-

5 larized Bells, of which the following description, in connection with the accompanying drawings, is a specification, like letters and figures on the drawings representing like parts.

10 This invention has for its object to improve the construction of polarized bells, whereby their strength and efficiency is greatly increased.

In accordance with this invention an elec-15 tro-magnet comprising two coils wound on suitable cores and attached to a heel-piece is secured to one end of a bent bar-magnet, each core of said electro-magnet having secured to it, preferably in an adjustable manner, a pole-piece.

20 A re-enforcing block, which constitutes the essential feature of my invention, is secured to the opposite end of the bar-magnet, to which the polarized armature is connected by means of a spring. This re-enforcing block 25 is made of iron and is recessed to receive and inclose one end of the polarized armature.

It is very desirable to attach the armature to the block by means of a spring, and to 30 give suitable length to the spring the re-enforcing block is formed with a boss or extension in or to which the spring is attached.

The bell-hammer is attached to the polarized armature by a hammer-carrying arm.

35 Figure 1 shows in plan, and Fig. 2 in side elevation, a polarized bell embodying this invention.

The base-plate *a*, preferably of metal, has secured to it a post *a'*, having two oppositely-40 extended arms *a²*, to which the gongs are attached, one or two being employed, as desired. A permanent or bar magnet *b* is also secured to the base *a*, it being bent and extended upwardly a little higher than the gong 45 to allow the bell-hammer to pass over the post *a'*.

An electro-magnet consisting of two coils *c c'*, wound on suitable cores and connected by a heel-piece *c²*, is secured to the lower end

of this bar-magnet on one pole thereof, said 50 cores having secured to their upper ends by means of screws two pole-pieces *c³*, made adjustable toward and from each other.

A re-enforcing block *d* is secured to the upper end of the permanent or bar magnet on 55 the opposite pole thereof, said block being made of iron or other suitable equivalent material. This block *d* is recessed, as at *d'*, at a point just over the upper end or pole of the bar-magnet. The block *d* has on it a boss or 60 projection *d²*, slotted down for a short distance. The polarized armature *e* has attached to it at one end a bell-hammer-carrying arm *e'*, which extends forward between the two gongs and carries the bell-hammer. 65 The armature *e* occupies a position between the two pole-pieces, and, extending rearwardly, enters the recess *d'* in the block *d*, terminating at a point just above the upper end of the bar-magnet. The armature *e* is 70 attached to a flat spring *e²*, which enters the slit in the boss or extension of the block, and is there secured by means of a pin 2 or otherwise. This block *d*, placed on one pole of the magnet, as shown, becoming saturated with 75 magnetism, presents a very strong field, in which the end of the armature *e* continually lies, and hence serves as a re-enforcing block for the armature. The block *d* also serves as 80 a very efficient means for holding the armature, so that in case an accident happens the armature can be replaced without necessitating the renewal of the bar-magnet.

I claim—

1. In a polarized bell, the combination of 85 the following elements: a base, a bent bar-magnet, an electro-magnet having two pole-pieces and connected to a heel-piece on one pole of the bar-magnet, a recessed and slotted re-enforcing block secured to the other pole 90 of the bar-magnet, a polarized armature, spring, bell-hammer, and carrying-arm therefor, and a gong, substantially as described.

2. In a polarized bell, a base, a bent bar-magnet, an electro-magnet having two pole-pieces oppositely arranged, and a heel-piece for 95 the electro-magnet secured to one pole of the bent bar-magnet, combined with a re-enforce-

ing block *d*, secured to the opposite pole of said bar-magnet, which is recessed at *d'* and has a slotted boss *d''*, the armature *e*, one end of which enters the recess *d'* in the block *d*, a 5 spring held in the slit in the boss supporting said armature, a bell-hammer, its carrying-arm, and a gong, substantially as described.

In testimony whereof I have signed my name to this specification in the presence of two subscribing witnesses.

ALBERT STORER.
